(57) **CLAIM**

The ornamental design for a surface ornamentation for wound therapy packaging, as shown and described.

DESCRIPTION

FIG. 1 is a top plan view of a surface ornamentation for wound therapy packaging, shown in use, showing my new design; and,

FIG. 2 is a top plan view thereof, shown in an enlarged scale. The broken lines in the figures illustrate the portions of the surface ornamentation for wound therapy packaging that form no part of the claimed design.

All sides not shown in the views form no part of the claimed design.

1 Claim, 2 Drawing Sheets
